UNITED STATES PATENT OFFICE.

EMIL EISELT, OF BALTIMORE, MARYLAND.

TRUCK SIDE FRAME.

Application filed June 9, 1923. Serial No. 644,481.

The invention relates to trucks for railway vehicles, and more particularly to new and useful improvements in the construction of truck side frames.

The principal object of the invention, generally considered, is to improve the construction of arch bar side frames. To this end the main feature of my invention consists in interposing between the compression and tension members or bars of an arch bar side frame a strut embodying as an integral casting upper and lower members connected by column portions which completely enclose the bolster opening, the said strut being rigidly connected to the arch bars and the latter having interlocking connections at points intermediate their ends.

Another object of the invention resides in the interlocking connection between the compression and tension members of the side frame at points intermediate the ends thereof.

Still another object consists in providing a strut member having integral top and column portions, the said column portions having aligned openings to receive one of the arch bars.

A still further object of the invention consists in combining with the tension and compression members of a truck side frame a combined strut, bolster guide and spring seat casting, the latter being of hollow box section and adapted to be interlockingly connected to adjacent portions of the said arch bars.

There are other objects of the invention as will hereinafter appear from the detailed description of the two embodiments thereof which are illustrated in the accompanying drawings, the novel features thereof being pointed out in the claims at the end of the specification.

Referring now to the drawings,

Figure 1 is a view partially in side elevation and partially in vertical section of a truck side frame constructed in accordance with my invention, the journal boxes and wheels being diagrammatically illustrated by dot and dash lines.

Figure 2 is a top plan view of the construction shown in Fig. 1.

Figure 3 is a transverse vertical sectional view taken substantially on the line 3-3 of Fig. 1, the direction of view being indicated by the arrows adjacent the ends of the said section line.

Figure 4 is a transverse horizontal sectional view on the line 4-4 of Fig. 1, the direction of view being indicated by the arrows adjacent the ends of the said section line.

Figure 5 is a transverse vertical sectional view taken on the line 5-5 of Fig. 1, the direction of view being indicated by the arrows adjacent the ends of the said section line.

Figure 6 is a transverse vertical sectional view through the arch bars at a point directly over the journal box indicated by the section lines 6-6 in Fig. 1 showing the interlocking connection between the bars at this point.

Figure 7 is a fragmentary view similar to Fig. 1, showing a slightly modified construction.

Figure 8 is a transverse vertical sectional view of the construction shown in Fig. 7, the view being taken on the line 8-8 of Fig. 7, looking in the direction indicated by the arrows.

Figure 9 is a transverse horizontal sectional view taken on the line 9-9 of Fig. 7.

Throughout the several views like parts are designated by like reference characters.

The side frame preferably comprises an upper arch bar or compression member 1, a lower arch bar or tension member 2, a strut 3, and pedestal tie bars 4.

The strut 3 is preferably formed as an integral casting and comprises a top member 5, columns 6, 6, and a bottom member or spring seat portion 7. The top member 5 is preferably of substantially I-beam or channel form having a web 8 and flanges 9, 9, the said flanges merging into the flanges of and being integrally connected to the webs 10 of the columns 6. The webs 10 terminate at points spaced from the web 8 to provide recesses 11, 11 through which the arch bar or compression member 1 is adapted to extend. Adjacent the lower ends of the webs 10 there are provided outstanding upwardly inclined flanges 12 which extend respectively from the outer faces of the said webs. Each flange 12 is preferably reinforced by an upright centrally arranged flange 13 and may be integrally connected to the flanges 14 of the columns 6.

On its under face the spring seat portion 7 is formed with a plurality of curved portions 15 which merge adjacent the center line of the truck into a reversely curved portion 16. The flanges 14 are adapted to extend

outwardly beyond and downwardly beneath the portions 15 and 16. The outwardly projecting portions of the flanges on opposite sides of the said strut are adapted to receive 5 and to be connected to the downturned flanges 17 of the pedestal tie bars 4.

Preferably at or near the center line of the side frame the web 8 is provided with a centrally arranged downwardly opening recess or depression 18 the purpose and object 10 of which will be hereinafter described.

Adjacent their outer ends and preferably at a point immediately above the vertical center line of the journal boxes the arch 15 bars are provided with interlocking bosses and recesses 19 and 20.

In the particular modification here illustrated the compression member or upper arch bar is formed at its center with a 20 curved boss or portion 21 adapted to seat within the correspondingly curved portion 18 of the web 8. These portions of the arch bar and compression member form an interlocking connection therebetween and assist 25 in maintaining the parts in proper assembled position. To prevent separation of the interlocked portions they are rigidly connected to each other by means of a rivet 22. If desired a plurality of rivets may be employed 30 for connecting the adjacent portions of the upper arch bar or tension member to the adjacent web 8 of the combined top member, bolster column and spring seat casting.

The lower arch bar or tension member is 35 provided adjacent its center with a plurality of curved portions 23 and 24 which are adapted, respectively, to engage the correspondingly curved portions 15 and 16, and conveniently the arch bar is connected to 40 the spring seat by means of a rivet or other suitable fastening means 25 which extends through the centering boss 26 and through the arch bar or tension member 2. It is to be observed that the tension member is 45 adapted to engage the faces of the flanges 12 and lies between the flanges 14 or the extensions thereof.

To reinforce and strengthen the lateral extensions 27, 27 and spring seat I preferably 50 provide marginal flanges 28 which project outwardly from the web 10 of the column 6.

Referring now to Figs. 7 to 9, inclusive, it will be seen that the combined top member, bolster column and spring seat casting is 55 substantially the same in construction as that illustrated in Figs. 1 to 6, inclusive, the only dissimilarity between the constructions here shown and that previously described being as follows:

60 The upper member 29 of the strut is of channel shape having downwardly extending flanges 30 between which and the web 31 of the said strut member the upper arch bar or compression member 32 is adapted to be 65 located. Adjacent the lower face of the

spring seat portion there is provided a single curved portion 33 against which the lower tension or arch bar member is adapted to engage and to which this member is connected by means of a rivet or other suitable fastening means 34.

In both constructions I have illustrated the column members as being provided with integral brake hanger brackets 35, and have shown as applied to the vertical faces of the 75 column portions bolster wear pads to increase the resistance to wear at the point of maximum relative movement between the bolster and the side frame. Except as before noted there is no other change in construction, since in both instances it will be understood that there is provided an interlocking connection between the arch bar members at or adjacent the journal boxes.

I claim:

1. In a truck side frame, the combination with a tension member and a compression member, of an interposed bolster guide and strut provided with a flanged bottom member, having intermediate said flanges a 90 curved portion adapted to seat upon said tension member, said strut also overlying the adjacent portion of said compression member, means for connecting said members to said strut, and means for interlockingly connecting said tension and compression members intermediate the ends thereof.

2. In a truck side frame, the combination with a tension member and a compression member, of a combined bolster guide member and strut, said member having a curved seat portion for said tension member and being further provided with curved portions adapted to interlockingly engage correspondingly formed portions of said tension and compression members, and means for connecting said members adjacent said interlocking portions.

3. In a truck side frame, the combination with upper and lower arch bars, of a strut interposed between the same, said strut comprising a hollow box member, portions of said strut enclosing portions of each of said arch bars, portions of said strut below said upper arch bar being spaced therefrom, and means formed on the strut and arch bars for interlockingly connecting the same.

4. In a truck side frame, the combination with upper and lower arch bars, of a strut interposed therebetween, said strut comprising a top member having a web and flanges depending therefrom, column portions and a spring seat portion formed integral with said top member, said upper arch bar being adapted to engage the undersurface of said web and spaced from the underlying portions of said strut, and means formed integrally with the arch bar and web for interlockingly connecting the same.

5. In a truck side frame, the combination

with upper and lower arch bars each of which is provided intermediate its ends with a curved portion, of a strut interposed between said arch bars, said strut having integral top and bottom members, said arch bars being adapted respectively to engage and extend beneath said members, said members having curved portions adapted to cooperate with said curved portions of said arch bars and rivet means for connecting said arch bars to the adjacent portions of said strut.

6. In a truck side frame, upper and lower arch bars, a strut interposed between and secured to the arch bars, the strut including a channeled top portion within which the upper arch bar lies, and further including columns channel shaped in cross section and having webs and side flanges, the strut further including a spring plank seat, the side flanges of the columns being prolonged downwardly and laterally, and tie bars secured to the strut at the lower corners thereof and lying between said prolongations, the lower arch bar engaging beneath the seat portion of the strut, and the strut having the lower ends of its column portions formed with bearing flanges inclined upwardly and outwardly with respect to the webs of the columns, said bearing flanges conformingly engaging against the top surface of the lower arch bar.

7. In a truck side frame, upper and lower arch bars, a strut interposed between and secured to the arch bars, the strut including a channeled top portion within which the upper arch bar lies, and further including columns channel shaped in cross section and having webs and side flanges, the strut fur-

ther including a spring plank seat, the side flanges of the columns being prolonged downwardly and laterally, and tie bars secured to the strut at the lower corners thereof and lying between said prolongations, the lower arch bar engaging beneath the seat portion of the strut, and the strut having the lower ends of its column portions formed with bearing flanges inclined upwardly and outwardly with respect to the webs of the columns, said bearing flanges conformingly engaging against the top surface of the lower arch bar, said columns having central vertical webs merging into said bearing flanges and acting to brace the same.

8. In a truck side frame, upper and lower arch bars, a strut interposed between and secured to the arch bars, said strut including a channel shaped top portion within which the upper arch bar lies and further including columns and a seat portion both channel shaped in cross section, the strut being formed at the center of its underside with a concavity and having curved portions merging into said concavity and extending upwardly, upwardly inclined bearing flanges formed on the columns and constituting continuations of and merging into said curved portions of the bottom, and reinforcing webs for said bearing flanges, the lower arch bar having a curved central portion and other curved portions thereadjacent conformingly engaging against the concavity and the curved bottom portions of the strut, the lower arch bar further engaging conformingly against said bearing flanges.

In testimony whereof I affix my signature.

EMIL EISELT.
